SLUG AND SLUG FEEDING APPARATUS

Oscar H. Goetz, Park Ridge, Ill.

Application March 14, 1934, Serial No. 715,420

8 Claims. (Cl. 194—4)

The present invention relates to slugs and slug feeding apparatus, and has particular reference to devices wherein the slug is fed into the machine by the movement of a slide or like feeding member. Coin feeding apparatus of this general type is extensively used in different coin controlled amusement devices and games, represented, for example, by the so-called "pin games" wherein rolling balls are deflected into numbered pockets by variously arranged pins; also by miniature baseball games, miniature boxers, target ranges, etc. It is desirable in many instances to have the feeding apparatus of these amusement devices and games of such construction as to be operable only when using authorized slugs which are coded for use in that particular type of machine or in the particular machines operated by one proprietor.

The general object of the invention is to provide improved slug feeding apparatus of the type employing a reciprocating slide or like slug feeding member; also to provide improved slugs for use with that apparatus. More specifically, this improved construction affords a coded arrangement between the feeding apparatus and the slug which gives maximum protection against the use of unauthorized slugs or coins.

In this regard, it is one of the more specific objects of the invention to provide an improved coded arrangement between the external periphery of the slug and the internal periphery of the slug receiving aperture which is carried by the feeding slide.

Another object of the invention is to provide an improved arrangement wherein the face of the slug is coded; i. e., to employ a code groove or recess formed in one or both faces of the slug adapted to coact with a matching guard or ward in the form of a projection, finger or the like disposed in the path of the slug as fed by the feeding apparatus.

Another object of the invention, as exemplified in one embodiment thereof, is to provide an improved apparatus which will be operable only by a slug which combines peripheral coding and face coding.

Other objects of the invention are to provide improved apparatus which will prevent operation of the machine by coins or slugs which are either too large or too small; which will prevent operation of the machine by unauthorized slugs having holes therein; and which will otherwise increase the dependability of this type of apparatus.

In the accompanying drawings illustrating certain preferred embodiments of my invention:—

Figure 1 is a horizontal sectional view through a machine embodying my improved slug feeding apparatus, this apparatus being illustrated in plan;

Figure 2 is a fragmentary vertical sectional view taken approximately on the plane of the line 2—2 of Figure 1;

Figure 3 is a front view of the feeding apparatus corresponding to a section taken on the plane of the line 3—3 of Figure 2;

Figures 4, 5, 6 and 7 illustrate four different forms of slugs each incorporating distinctive peripheral coding;

Figure 8 is a fragmentary plan view of a modified construction of feeding apparatus for feeding slugs which are coded both on their peripheries and on their faces;

Figure 9 is an edge view of such a slug;

Figure 10 is a face view thereof;

Figures 11 and 12 are detail views taken approximately on the plane of the line 11—11 of Figure 8 and illustrating, in different positions, one of the locking dogs for cooperating with the peripheral and face recesses of the slug;

Figure 13 is a fragmentary perspective view illustrating the coaction between such locking dogs and the slug;

Figure 14 is a vertical sectional view through another modified construction of feeding apparatus;

Figure 15 is a transverse sectional view taken approximately on the plane of the line 15—15 of Figure 14, but on a larger scale;

Figure 16 is a face view of the form of slug for use with the latter embodiment of feeding apparatus; and

Figure 17 is a face view of another slug having face coding on each side so that the slug is reversible.

The front casing wall of the slug controlled machine is fragmentarily illustrated at 21. The reciprocable slide which feeds the slugs into the machine is indicated at 22, this slide entering the casing 21 through an opening 23, said opening being covered by a face plate or cover fitting 24. The cover fitting 24 is secured to the casing by screws 25 which are only removable from the interior of the casing. Said fitting has a horizontal slot 26 therein, through which the slide 22 moves. The vertical flange of an L-shaped bracket or plate 27 is secured to the back side of the cover plate 24 by rivets 28, as best shown in Figure 2. The rearwardly extending horizontal portion of the member 27 lies above or flush with the top edge of the slot 26 so that the slide 22 passes under

- the member 21. The slide rests on a lower plate 29 which is spaced below the bracket member 21. The bracket member and plate are secured together beyond the side margins of the slide 22 by rivets, staking pins or the like, 31. The plate 29 projects forwardly through and beyond the cover fitting 24 to form a front shelf portion 29a over which the slider 22 is adapted to slide. The side margins of this front shelf portion are bent upwardly and then turned inwardly to form the guide flanges 29b, which overlie the side margins of the slider 22 and guide the latter in its reciprocating motion. These guide flanges preferably terminate substantially at the front face of the cover fitting 24. The plate 29 extends considerably to the rear of the cover fitting 24, and has an upwardly bent flange 29c at its rear end, this flange having a horizontal slot 29d punched therein, through which the slider 22 slides.
- 20 The limits of movement of the slide are determined by a stop member in the form of a clip 32, which has suitable attachment to the plate 29, as by the screw 33 and by spur extensions 32' of the clip which are turned down into slots punched in the plate 29. The adjacent margin of the slide 22 has a long recess or slot 22a formed therein, terminating in shoulders 22b and 22c. The outward limit of movement of the slide is defined by the shoulder 22b striking one end of the clip 32, 30 and the inward limit of movement is defined by the other shoulder 22c striking the other edge of the clip. The slide is normally held in its outward position by a tension spring 34 which has one end hooked to a pin or aperture 35 carried by 35 the guide plate 29, and which has its other end hooked to a pin or projection 36 carried by the slide 22, this spring normally holding the stop shoulder 22b against the stop clip 32.
- The last bit of inward motion of the slide is 40 adapted to effect the tripping, releasing or actuating function, which sets into motion or into operativeness the machine or device controlled by the slugs. The inner extremity of the slide, or any suitable projection on the slide, may be 45 arranged to perform this function; in the illustrative arrangement, a pin 37 projects upwardly from the slide and is adapted to engage and oscillate a crank arm or finger 38, such merely exemplifying typical apparatus to be actuated by 50 the slide.
- Cooperating with the other side edge of the slide is a full-stroke pawl 41 which functions in such a manner that after the slide has completed a certain amount of inward movement it cannot 55 be retracted until its full inward stroke has been completed. This pawl is pivotally mounted on the stud 42 suitably carried by the supporting plate 29. A nose 41a projects from this pawl for swinging movement in a path which intersects the adjacent edge of the slide. A tension spring 43 is connected between an arm of this pawl and the flange 29c of the supporting plate, the action of this spring being such as to tend to swing the nose 41a into a position lying substantially at right 60 angles to the adjacent edge of the slide. A reversing notch 22d is formed in this edge of the slide preferably at a point which will dispose this notch slightly forward of the pawl when the slide is in its forward or retracted position. When the slide 65 is pressed inwardly the nose 41a of the pawl oscillates into the reversing notch 22d and the pawl is swung around with the continued inward movement of the slide until the pawl nose is oscillated out of the notch, in which position the pawl nose 70 faces rearwardly or oppositely to that shown, at 75

which time the spring 43 tends to swing the pawl back in the reverse direction. As the slide approaches the inward limit of its movement, a series of V-shaped blocking notches 22e in this edge of the slide move past the nose of the pawl. 5 If it should be attempted to have the slide move outwardly at this time, the nose 41a of the pawl 41 will abruptly engage one of the shoulders of the blocking notches 22e and positively prevent such outward movement. As the slide nears the inward 10 limit of its movement, a second reversing notch 22f comes into registry with the pawl nose 41a. This notch is sufficiently wide and deep to permit reverse oscillation of the pawl, and hence after this notch has come into registry with the pawl, 15 or has moved past the pawl, the slide is free to move outwardly in its return motion, the pawl oscillating through said latter notch to resume its former position, which is the position illustrated in Figure 1.

As best shown in Figure 2, the supporting plate 29 is provided with three holes 45, 46 and 47, located at different points along its length. The hole 45 is located outside of the casing 21, and the other two holes, 46 and 47, are located inside of 25 the casing. The two inner holes discharge into any suitable coin receptacle or coin chute, such being typically represented by the space 48 defined between the front casing wall 21 and a rearwardly disposed wall 49.

The slide 22 has a slug receiving aperture 51 which is adapted to register in sequence with each of the holes 45, 46 and 47. The outer hole 45 is positioned to lie beneath the slug conveying aperture 51 when the slide is in its normal position. Preferably, this outer hole is of small diameter and its principal purpose when of small size is to enable a tool to be inserted up through the hole for dislodging from the slug conveying aperture 51 any coin or slug which may have become 40 jammed therein. The second hole 46 has the function of ejecting from the slug conveying aperture 51 any small spurious slugs or small coins, whereby to prevent the fraudulent operation of the machine by such slugs or coins. For example, 45 in machines where the coded slugs are intended to have a token value of a nickel, it is desirable that smaller slugs, pennies, etc., shall be incapable of remaining in the slug conveying aperture 51 for operating the machine. If the code 50 projections extending inwardly from different peripheral points of the aperture 51 will permit the introduction of a penny between the inner extremities of these code projections, the ejecting hole 46 should be of sufficient size to result in 55 the dumping of such penny from the conveying aperture as the latter passes over the ejecting hole 46. This ejecting hole can be made of any desired size or shape so long as the side margins thereof adjacent to the sides of the supporting 60 plate 29 afford shelf supporting areas on which the side margins of an authorized slug can ride. In the preferred construction shown, the spurious slugs or coins discharged through the hole 46 are dumped down into the coin receptacle 48, al- 65 though, if desired, they might be dumped into a separate chute leading to a coin return pocket at the front of the machine. The first hole 45 may also be made of sufficient size to dump pennies and spurious slugs, although for certain 70 formations of coded slugs this hole should be of sufficiently small size to prevent the code projections on the slug from jamming in said hole in any slanting or edgewise insertion of the slug into the aperture 51. The third hole 47 is rela- 75

tively large and serves to discharge the authorized slugs into the receptacle 48 when the slide is approaching the inner limit of its movement.

For arresting the motion of the slide in the absence of an authorized slug in the conveying aperture 51, there is provided blocking mechanism including a testing finger 52 and a blocking dog 53 arranged above the slide directly back of the casing wall or cover fitting. The finger and dog oscillate vertically on a transverse pivot shaft 54 and they can be connected together in any suitable manner, preferably by forming the two members as the side portions of a single U-shaped stamping so that they are joined together by the back or connecting portions 55. A wire spring 56 has its ends coiled around the pivot shaft 54 and hooked over the testing finger 52 and blocking dog 53, with the intermediate portion of the spring bearing against the top of the mounting bracket 27, the action of this spring being to swing the finger and dog downwardly. The ends of the pivot shaft 54 are mounted in pivot lugs 57 projecting upwardly from the bracket 27. The testing finger is adapted to swing down through a slot 58 which is punched in the mounting bracket substantially in the medial line of the slider 22, and the blocking dog 53 is adapted to swing down through a slot 59 which is punched in this bracket at a point above the marginal portion of the slide. The slide presents a solid surface for engagement by the point of the testing finger 52 up to the aperture 51. If an authorized slug is within this aperture, the finger is maintained in its elevated position throughout the entire inward stroke of the slide. If, however, the aperture 51 is empty, or if the token therein drops down through the ejecting hole 46, the finger promptly swings down into the aperture and enables the blocking dog 53 to also swing downwardly. This brings the nose of the blocking dog down into a notch 22h in the adjacent margin of the slide so that further inward movement of the slide is blocked by the outer shoulder of this notch abutting the front side of the blocking dog. Hence, the absence of a slug or the dumping of a spurious slug or coin down through the rejecting hole 46 will result in the motion of the slide being blocked before it can complete its inward movement. The slide is retractable from this blocked position, however, for subsequent operation by authorized slugs. It will be noted that the spring pressure exerted downwardly through the testing finger 52 will aid in discharging down through the rejecting hole 46 any improper token which does not have shelf support at the sides of the hole 46. The location of this testing finger is also such that, should any unauthorized slug having a central hole therein be inserted in the machine, this finger will swing down into said hole in the slug and block further movement of the slide. Should it be desired to provide the authorized slugs with central holes, for sorting purposes or the like, the testing finger 52 can be positioned slightly to one side so that it will not enter these holes in the slugs. Forwardly of the conveying aperture 51, an inclined groove 61 slopes upwardly from the aperture to the top surface of the slide in the median plane of the slide, this groove avoiding the presence of any interfering shoulder beyond the margin of the slug which might strike the testing finger 52 if the authorized slug happened to be slightly thinner than the depth of the aperture 51.

75 In the preferred embodiment of my invention,

I associate an ejecting and stopping device with the inner hole 47 through which the authorized slugs are finally discharged into the receptacle 48, this ejecting and stopping device being advantageous in affording additional protection against unauthorized operation, although not being essential to the successful use of the machine. Such device comprises a lever 64 having rockable mounting on a pivot shaft 65 and including a forwardly extending arm 64a and a rearwardly extending arm 64b. The downturned end of the forwardly extending arm is disposed substantially above the center of the discharge hole 47 and, as viewed in plan, is disposed substantially medially of the slide, where a solid surface of the slide 15 will be presented to the point of the lever arm 64a extending up to the aperture 51. The rearwardly extending arm 64b is offset laterally to lie in another plane, as shown in Figure 1. In this other plane the slide is provided with a longitudinal slot 66 terminating in a stop shoulder 66a at the forward end of the slot. The pivot shaft 65 has its ends mounted in lugs 67 projecting from or carried by the end flange 29c of the supporting plate 29. A coil spring 68, mounted on the pivot shaft, tends to press the lever arm 64a downwardly against the top of the slide. When the slug arrives in its dischargeable position over the discharge hole 47 the spring pressure acting downwardly through the lever arm 64a tends to 30 press the slug downwardly out of the aperture 51. The slug arrives in this position before the completion of the full operative stroke of the slide and, in this position, the stop shoulder 66a is in close proximity to the rearwardly extending lever 35 arm 64b. If the spring pressure exerted downwardly against the slug is not sufficient to discharge it through the hole 47, continued inward movement of the slide will cause the stop shoulder 66a to exert a camming pressure against the 40 lever arm 64b for exerting mechanical pressure downwardly against the slug for causing its discharge. If this pressure is still insufficient to cause the release of the slug, the engagement of the stop shoulder 66a against the lever arm 64b 45 will prevent the slide from completing its full inward stroke through the distance required to operate the actuating device 38. The slide, however, may be pulled back out to its original position for releasing the slug from the aperture at 50 the front of the machine. The above described device prevents the fraudulent operation of the machine by wedging or sticking a slug within the aperture 51 in such manner that it will not drop out of said aperture, under which condition the 55 machine could be operated repeatedly with one slug. When this ejecting and stopping device 64 is employed, the full stroke mechanism is preferably so arranged that the first of the blocking notches 22e will not have reached the pawl 41 60 at the time that the lever arm 64b is in engagement with the stop shoulder 66a, preparatory to stopping further inward movement of the slide, should the ejecting device be incapable of ejecting the slug from the aperture 51. Thus, if the 65 slug cannot be ejected down through the discharge opening 47 the slide can still be retracted back to its normal position for a forcible ejection of the slug from the front of the machine. The point at which the motion of the slide is arrested by any such jammed slug is short of the point at which the slide transmits operative movement to the actuating member 38.

70 Referring now to the peripheral coding of the aperture 51 and its authorized slug, in the em- 75

bodiment illustrated in Figure 1, the aperture is peripherally coded by forming in its periphery the uniformly spaced teeth or projections 71 with the alternating tooth spaces or recesses 72. The 5 authorized slug 74 for such recess is illustrated in Figure 4. Its periphery has the alternating tooth spaces 75 and tooth projections 76, which are adapted to have a relatively close matching fit with the tooth projections 71 and tooth spaces 72 in the aperture 51. Where the slug 74 is to have the token value of a nickel the coding formation within the aperture 51 has a minimum diameter such as will preclude the introduction of a nickel, or a plain slug of nickel size, into the 10 aperture. That is to say, the points of the tooth projections 71 in the aperture 51 define or circumscribe an inner diameter, which I have designated by the circle D1 in Figure 1, which circle is smaller than the diameter of a nickel or of a plain 15 slug of nickel size. The bottom ejecting hole 46 is of the same size as this circle D1, or slightly larger. Hence a penny or any other token, which is receivable within the circle D1 defined by the 20 points of the tooth projections 71, will pass down through the ejecting hole 46 as soon as the aperture 51 moves over the hole. It will be evident that a wide variety of coded arrangements 25 can be obtained by merely increasing or decreasing the total number of tooth projections around the slug 74 and the total number of tooth spaces within the aperture 51. Another method of changing the coded arrangement is to increase or decrease the overall diameter of the slug 74. This over-all diameter is designated by the outer 30 circle D2 (Figure 4) defined by the points of the tooth projections 76 of the slug. The ejecting hole 46 has a cross dimension measured transversely of the supporting plate 29 which is less than this large diameter D2. The inner diameter 35 D1 of the aperture can also be changed for changing the coded arrangement. In localities where there is prevalent use of telephone slugs of the general pattern having a serrated periphery, substantially as illustrated in Figure 4, a differentiation 40 may be effected by changing the number of tooth projections 76 on the slug, or by increasing or decreasing the outer diameter D2, so that the amusement slug is not usable in the telephone 45 and so that the telephone slug is not usable in the 50 amusement device.

The peripheral coding may be obtained by other formations such as those illustrated in Figures 5, 6 and 7. Figure 5 illustrates the slug and aperture as being of polygonal form, represented by 55 a hexagon, octagon, etc. The flat code surfaces 78 defined within the conveying aperture 51 circumscribe or outline the aforesaid inner circle or minimum diameter D1, which is smaller than a nickel, so that a nickel or plain slug of nickel 60 size cannot be inserted into the aperture. The two diametrically opposite points 79, 79 of the slug lying on a diameter extending transversely of the motion of the slide establish points or areas for shelf-support along the lateral margins of 65 the ejecting hole 46.

In Figure 6 the aperture 51 is provided with one or more inwardly extending projections 81, the remainder of the aperture between said projections being smooth. The slug has matching recesses 82 adapted to register with the projections 81. The inner circle or minimum diameter D1 is circumscribed within the points of the projections 81, the ejecting hole 46 having a transverse dimension corresponding to this diameter. The 70 portions 83 of the slug projecting outwardly be-

yond the circle D1 in a direction transverse of the motion of the slide afford the supporting areas on the slug for shelf-support along the lateral margins of the ejecting hole 46.

In the form shown in Figure 7, the slug has 5 one or more flat sides 84. The proportions are such that the inner diameter D1, which can be inscribed between these flat sides, is smaller than a nickel so that a nickel cannot be inserted into the aperture. In any such coding arrangement 10 using two flat sides 84, these sides should preferably be arranged at an angle to the direction of motion of the slide so that the extending portions 85 of the slug projecting beyond the inner diameter D1 will be so located that they will ride on 15 the shelf supporting areas at the margins of the ejecting hole 46.

From the preceding description of the different peripheral code formations of Figures 4, 5, 6 and 7, it will be seen that three features are prevalent 20 in the different embodiments: First, the projections extending inwardly from the aperture 51 circumscribe an inner circle D1 which is smaller than a nickel so that a nickel cannot be used; second, the ejecting hole 46 is of substantially the 25 same size as this inner diameter D1 so that whatever coin or token can be inserted within said inner diameter D1 will be ejected down through the discharge hole 46; and, third, irrespective of the formation of the authorized slug, when 30 such slug is in its proper position in the aperture 51 it should have side portions in position to ride upon or have shelf support on the side margins of the ejecting hole 46. Figure 4 illustrates this relation. The aforesaid shelf supporting areas at 35 the sides of the ejecting hole 46 are designated 86. The dash and dot lines 87 indicate the lines beyond which the authorized slug should have some portion of its coded periphery extending in a direction transverse to the direction of motion 40 of the slide for riding on the shelf supporting areas 86. For example, if the aperture for the 45 slug of Figure 7 were arranged at right angles to the position shown, with no portion of the slug projecting laterally beyond the minimum diameter D1 or the space between the lines 87, there would be no support for the travel of the authorized slug over the ejecting hole 46, and such slug would be ejected down through the hole.

In Figures 8 to 13, inclusive, I have illustrated 50 a modified construction which combines face coding of the slug with peripheral coding thereof. The face coding is shown as comprising two parallel slots or grooves 91 extending across one face of the slug 74a. At both ends of each groove the 55 metal is punched entirely through the depth of the slug to form the recesses 92 extending into the ends of the grooves 91. As best shown in Figures 11 and 12, the inner ends of these recesses 92 form abutment shoulders 93. It is necessary that when the slug is introduced into the conveying aperture 51 the face grooves 91 be parallel with the direction of motion of the slide. This is insured by providing code projections 94 60 extending inwardly from one or more points in the periphery of the aperture 51 for reception in correspondingly shaped recesses 95 in the edge of the slug. These projections and recesses 94, 95 preclude the introduction of the slug into the aperture 51 in any position other than with the 65 grooves 91 aligned with the direction of motion of the slide. The projections 94 and recesses 95 also establish peripheral coding between the aperture and the authorized slug, this coding precluding the insertion of a nickel or of a plain 70

slug of nickel size into the aperture, as previously described. Other peripheral coding arrangements may be employed if desired. The face grooves 91 and the peripheral recesses 92 and shoulders 93 code the slug with respect to motion so as to control the ability to reciprocate the slide 22 inwardly to the full length of its stroke.

This coding against motion utilizes two arresting pawls 97, 97 which are pivotally mounted within the casing 21 in planes coincident with the vertical planes of the code grooves 91, 91 in the slug. The two pawls are pivotally mounted on a transverse shaft 98 having its ends supported in lugs 99 extending upwardly from the bracket member 27. Coil springs 101 encircle the shaft 98 and have their ends arranged to urge the extremities of the pawls downwardly. Each pawl extends downwardly through a relatively wide slot 102 provided in the bracket plate 27 in the plane of each pawl. The slide 22 is provided with two parallel slots 103, 103 punched entirely through the body of the slide and extending from the inner side of the aperture 51 toward the rear end of the slide. These slots are in the same longitudinal planes as the slug grooves 91 and the arresting pawls 97. Extending forwardly or outwardly from the other side of the aperture 51 are grooves 103', 103' which are formed in the slide in the same longitudinal planes as the slots 103, the outer ends of these grooves sloping upwardly to the surface of the slide, as shown in Figures 11 and 12. Each pawl carries a transverse pin 104 which has its ends projecting from opposite sides of the pawl. The slots 102 are made sufficiently wide to allow the projecting ends of these pins to pass down therethrough. The lower slots 103 formed within the slide are only slightly wider than the thickness of each pawl, and hence the ends of the pins 104 can ride on the top surface of the slide along the margins of these slots 103. Such relation utilizes the top surface of the slide as a gauge surface for determining how far the extremities of the pawls extend down into the slots 103, this being one manner of gauging, although not an essential practice as the lower extremities of the pawls might rest on a flat lower surface below the slide. For example, if an ejecting hole 46 is provided which extends below the pawls 97, the use of an upper gauge surface is desirable. The slots 103 may be made of sufficient length so that the extremities of the pawls normally lie in these slots when the slide is in its normal retracted position, or the pawls may be arranged to drop into these slots shortly after the slide starts its inward movement.

Each pawl is formed with a relatively narrow nose extremity 106 which is capable of entering the peripheral recess 92 and face groove 91 in the slug, the remainder of the pawl above this nose being wider than said recess and groove. The front side of the nose forms an abrupt arresting shoulder 107 adapted to lie in the path of movement of the slug. The laterally extending shoulders 108 at the upper end of the reduced nose portion 106 are sloped to form inclined cam surfaces. These cam surfaces are adapted to be engaged by the top edge of the authorized slug substantially at the points 109, 109 (Figure 13) adjacent to the inner margins of the recesses 92 or grooves 91.

The two pawls 97, 97 function to arrest the motion of the slide 22 should any unauthorized slug or token not having the face and peripheral coding 91, 92 be inserted into the conveying aperture 51. For instance, the introduction of any

unauthorized slug having the peripheral coding 95 would result in such slug moving inwardly with the slide until the solid edge portion of the slug encountered the two abutment shoulders 107 of the two pawls, whereupon further motion of the slug and slide would be arrested. Similarly, any coin or token receivable within the inner diameter D1 defined by the peripheral code projections 94 of the aperture would still present a solid edge to the shoulders 107 of the pawls, with the result that the motion of the slide would be arrested. Likewise, if any slug having the face grooves 91, but not having the peripheral recesses 92 (substantially like the slug illustrated in Figure 16) should be inserted into the aperture, the solid edge portions 15 of the slug would strike the shoulders 107 of the pawls before any lift could be transmitted through the cam surfaces 108 to the pawls. However, when the authorized slug of Figure 10 moves rearwardly in the slide, the nose extensions 106 of 20 the pawls are accommodated within the peripheral recesses 92 as the slug continues its rearward movement. Before the shoulders 93 at the inner ends of these recesses 92 strike the shoulders 107 of the pawls, the points 109 on the advancing top 25 edge of the slug have encountered the cam surfaces 108 and are lifting the pawls upwardly. The parts are so proportioned that this cam lifting action raises the extremity of each pawl just sufficient to clear the shoulder 93, so that during 30 continued rearward movement of the slug the nose of the pawl rides in the associated groove 91. The rear points of the cam surfaces 108 ride on the side margins 91', 91' of each groove 91 so that the pawl is held in elevated position as the other 35 side of the slug passes beneath the pawls, the pawls riding up through the inclined grooves 103' to the surface of the slide during the latter part of the actuating stroke.

The two pawls 97, 97 may be utilized to block the motion of the slide in the complete absence of any slug or token in the aperture 51, as by having the shoulders 107 of the two pawls engage the opposite or outer edge of the aperture, as for example the shoulders or surfaces 111 at the inner ends 45 of the sloping grooves 103'. An alternative or supplementary arrangement for blocking the motion of the slide in the absence of an authorized slug in the aperture includes the use of the previously described testing finger 52 and blocking dog 50 53, substantially in the relation illustrated in Figures 1 and 2. The finger and the dog can be constructed as a single U-shaped member, with the back part of the member extending around one of the pawls 97. As before described, the dog 55 53 is adapted to swing down into a notch 22h in the adjacent margin of the slide for encountering the shoulder at the outer end of this notch if it should be attempted to push the slide inwardly without any slug in the aperture 51. This blocking function would be arranged to occur before the shoulders 111 in the aperture 51 could engage the shoulders 107 on the pawls 97. The slide can always be retracted to its normal position from any blocked condition which has been 60 established either by the pawls 97 or by the blocking dog 53, the pawls and dog being cammed back up to their normal positions by the outward movement of the slide. Any attempt to use an unauthorized token of sufficiently small size to pass 65 between the two pawls 97 will cause the same blocking to occur as if no token were in the aperture, because the pawls will then engage the shoulders 111 on each side of the token. As a further safeguard, the first hole 45 and the inter- 70 75

mediate hole 46 may be proportioned in size so as to discharge any such token which might be sufficiently small to pass between the pawls. As above remarked, the plate 29 may be solid below the pawls 97, or the ejecting hole 46 may be provided, having the width and ejecting relation described of Figure 4. Where the ejecting hole is employed it may be positioned or extended more forwardly, so that small spurious tokens will be ejected through this hole before the edges of such tokens forcibly abut against the shoulders 107 of the pawls.

The code combination for the above described construction can be readily changed by changing either the number of face grooves 91 in the surface of the slug or the spacing between the grooves or both, and correspondingly changing the number of pawls 97 or their transverse spacing on the shaft 98. The peripheral coding 94, 95 can also be changed for different combinations. The full-stroke mechanism 41, etc. cooperates with this embodiment in substantially the manner previously described, and the ejecting and stopping device 64, etc. can also be associated with this embodiment if desired.

In the construction shown in Figures 14, 15 and 16, the slug 74b has face coding in the form of two parallel grooves 115 extending across the face of the slug, and has peripheral coding in the form of recesses 95 adapted to register with projections 94 in the conveying aperture 51. The blocking means coacting with the grooves 115 consist of a stationary plate 116 having depending lugs 117 adapted to register with the grooves. The plate 116 is fixedly mounted behind the cover plate 24, preferably being secured between this cover plate and the vertical flange of the L-shaped bracket 27. The top surface of the slide 22 is provided with two parallel grooves 118 which are spaced to register with the grooves 115 in the slug. The grooves 118 extend inwardly beyond the aperture 51, as shown in Figure 14, and extend outwardly a distance sufficient to accommodate the full stroke of the slide, so that the registration lugs 117 are in the slide grooves 118 or in the slug grooves 115 in all positions of the slide. It will be seen that if any unauthorized slug, not having the grooves 115, be inserted into the aperture, the edge of such slug will strike the lugs 117 and will prevent further inward movement of the slide. A testing finger 52 and blocking dog 53 are arranged adjacent to the ejecting hole 46 for blocking continued movement of the slide in the absence of an authorized slug within the aperture 51, substantially as described of the embodiment illustrated in Figures 1 and 2. Here, again, the code combination can be changed by varying the number of grooves 115 and the spacing between these grooves, with corresponding variations of the registration lugs 117; also, by varying the peripheral coding 94, 95. The full stroke mechanism 41, etc., and the ejecting and stopping mechanism 64, etc., can also be employed with this embodiment. The ejecting hole 46 has the same width and ejecting relation as previously described in connection with Figure 4.

In Figure 17 I have shown a slug 74c which is somewhat similar to that shown in Figure 16, but which is reversible so that it will operate with either side up. Two parallel grooves 121, 122 are formed in one face of the slug, the groove 121 being adjacent to one edge and the groove 122 being adjacent to the middle. On the reverse side of the slug two similar grooves 121' and 122' are provided in the same spaced relation but

shifted so that the groove 121' is located adjacent to the opposite edge and the groove 122' is located to the opposite side of the middle. The lugs 117 on the plate 116 would of course have this same relation to the slot 26. It will be evident that either side of the slug can be turned up for passing through the slot 26 when the slug is turned over about an axis parallel with the grooves. The periphery of the slug has two code notches 123 therein for registration with correspondingly placed code projections (like the code projections 94) in the aperture 51. The angular relation of the code notches 123 insures that the grooves 121, 122 or 121', 122' will be lined up parallel to the motion of the slide and in proper transverse relation when either side of the slug is uppermost in the aperture. When using this type of slug having code grooves in both faces of the slug, I may also provide a bottom pair of stationary code projections 117 arranged to extend up from the supporting plate 29 for reception in the bottom grooves of the slug, in the same way that the top code projections 117 are received within the top grooves of the slug. The slug would still be reversible when using the upper and lower pairs of code lugs 117. The under side of the slide 22 would also have a bottom pair of grooves or recesses 118 in alignment with the bottom grooves of the slug.

While I have illustrated and described what I regard to be the preferred embodiments of my invention, nevertheless it will be understood that such are merely exemplary and that numerous modifications and rearrangements may be made without departing from the essence of the invention. For example, the outer hole 45 in each of the above described embodiments may be made to have an ejecting function like the hole 46, by giving this outer hole 45 substantially the same width as the circle D1, particularly when using coded slugs which do not have a large number of peripheral projections which might become jammed in said hole 45 in any slanting introduction of the slug. It will also be understood that in adapting the mechanism to the use of authorized slugs having a token value other than a nickel, such as for slugs having the token value of a quarter, appropriate changes can be readily made in proportions for precluding the introduction of spurious coins and slugs into the aperture 51, or for ejecting such spurious coins and slugs from said aperture, represented, for example, by nickels, pennies and dimes and unauthorized slugs, without departing from the invention.

I claim:—

1. In slug controlled apparatus including a housing having mechanism therein adapted to be operated, the combination of a supporting plate, a slide reciprocable on said plate and including actuating means adapted to operate said mechanism, a slug conveying aperture in said slide, said slide being movable from a normal position where said aperture is outside of said housing to a completely actuated position where said aperture is inside of said housing and where said mechanism has been operated by said actuating means, an authorized slug having the token value of a nickel adapted for insertion into said aperture, a code formation in the edge of said aperture including code projections extending inwardly and circumscribing an inner circle of smaller diameter than a nickel so that a nickel cannot be inserted into said aperture, an ejecting hole in said supporting plate positioned to eject unauthorized tokens from said conveying

aperture before said slide can be moved to its completely actuated position, the width of said ejecting hole measured transversely with respect to the motion of said slide being substantially the same as the diameter of said inner circle, whereby any token receivable within the area of said inner circle will be discharged through said ejecting hole, the side margins of said ejecting hole defining shelf areas extending parallel to the motion of said slide, a code formation in the periphery of said authorized slug matching with the code formation in said aperture, the code formation in said slug including portions extending beyond said inner circle in a direction transverse with respect to the motion of said slide for support on the shelf areas at the side margins of said ejecting hole, mechanism for blocking the motion of said slide in the absence of a slug in said aperture or in the event of the ejection of an unauthorized slug or token through said ejecting hole, a lever disposed in said housing and pivotally mounted intermediate its ends, one arm of said lever being arranged to exert positive ejecting pressure against said slug for ejecting it from said aperture prior to said actuating means causing the normal operation of said mechanism, and a shoulder on said slide adapted to engage the other arm of said lever for causing slug ejecting motion of said lever, said shoulder and lever blocking the motion of said slide short of the point where said slide effects normal operation of said mechanism if said lever is incapable of ejecting the slug from said aperture.

2. In apparatus of the class described, the combination of a stationary support, a slide reciprocable on said support between innermost and outermost positions, a conveying aperture in said slide adapted to receive an authorized slug when said slide is in its outermost position, an authorized slug having the token value of a nickel adapted for insertion into said aperture, a code formation in the edge of said aperture including code projections extending inwardly and precluding the introduction of a nickel into said aperture, a code formation in the periphery of said authorized slug matching with the code formation in said aperture, an ejecting hole in said stationary support positioned to eject unauthorized tokens from said conveying aperture before said slide has been reciprocated to its innermost position, said ejecting hole being of a size to eject from said aperture tokens which are receivable between the inner extremities of the code projections in said aperture, but being incapable of ejecting authorized slugs from said aperture, means responsive to the absence of a slug in said aperture for arresting motion of said slide towards its innermost position, and ejecting and stopping mechanism comprising a lever pivotally mounted intermediate its ends, one arm of said lever being arranged to exert positive ejecting pressure against said slug for ejecting it from said aperture when said slide is approaching its innermost position, and a shoulder on said slide adapted to engage the other arm of said lever for causing slug ejecting motion of said lever, said shoulder and lever blocking the motion of said slide short of its innermost position if said lever is incapable of ejecting the slug from said aperture.

3. In slug controlled apparatus including a housing having mechanism therein adapted to be operated, the combination of a supporting plate, a slide reciprocable on said plate and in-

cluding actuating means adapted to operate said mechanism, a slug conveying aperture in said slide, said slide being movable from a normal position where said aperture is outside of said housing to a completely actuated position where said aperture is inside of said housing and where said mechanism has been operated by said actuating means, a pawl mounted within said housing and operable to engage the edge of an unauthorized token within said aperture before said slide has been moved to its completely actuated position, and an authorized slug receivable in said aperture and having a code groove formed in one face thereof for receiving said pawl.

4. In slug controlled apparatus, the combination of a movable member adapted to have a predetermined range of movement, slug conveying means moving therewith, an authorized slug adapted to be conveyed thereby, said slug having a code groove formed therein extending across one of the flat faces of said slug, a pawl adapted to block motion of said movable member when engaging the edge of an unauthorized slug, and a cam surface on said pawl engaged by a portion of said authorized slug for moving the nose of said pawl into said code groove.

5. In slug controlled apparatus, the combination of a movable member adapted to have a predetermined range of movement, slug conveying means moving therewith, an authorized slug adapted to be conveyed thereby, said slug having a code groove extending across one of the flat faces thereof and having a notch extending through the entire thickness of said slug at one end of said groove, a pawl disposed in the path of movement of said slug conveying means for arresting motion of said movable member when conveying an unauthorized slug, the nose of said pawl being receivable in the notch of said authorized slug, and a cam surface on said pawl engaged by the edge of said authorized slug for raising the nose of said pawl into said code groove.

6. In slug controlled apparatus, the combination of a movable member adapted to have a predetermined range of movement, a slug receiving aperture therein, an authorized slug for reception therein having a code groove extending across one of the flat faces of said slug, a code formation in said aperture and a code formation on said slug compelling the reception of said slug in said aperture in position with said groove extending parallel to the line of movement of said movable member, and a member having blocking coaction against the edge of an unauthorized slug but receivable in said code groove of the authorized slug for permitting continued movement of said movable member.

7. In apparatus of the class described, the combination of a stationary support, a movable member adapted to have a predetermined range of movement relatively to said support, a slug receiving aperture in said movable member, an authorized slug for reception therein having a code groove extending across one of the flat faces of said slug, a code device carried by said support having blocking coaction against the edge of an unauthorized slug but receivable in said code groove of the authorized slug for permitting continued movement of said movable member, and a recess in said movable member coextensive with the code groove in said slug for accommodating said code device through the predetermined range of movement of said movable member.

8. In apparatus of the class described, the combination of a stationary support, a movable member adapted to have a predetermined range of movement relatively to said support, a slug receiving aperture in said movable member, an authorized slug for reception therein having a code groove extending across one of the flat faces of said slug and having a code groove extending across the other of said flat faces, a code device carried by said support having blocking coaction against the edge of an unauthorized slug but re-

ceivable in one of said code grooves of the authorized slug for permitting continued movement of said movable member, and peripheral registration means in said aperture and on said slug for compelling the reception of said slug in said aperture in position with one of said grooves extending parallel to the line of movement of said movable member irrespective of which side of said slug is uppermost.

OSCAR H. GOETZ. 10
